GAS COOLER

Filed Oct. 12, 1922

Patented June 10, 1924.

1,497,238

UNITED STATES PATENT OFFICE.

HENRY HOWARD, OF CLEVELAND, OHIO, ASSIGNEE TO THE GRASSELLI CHEMICAL COMPANY, OF CLEVELAND, OHIO, A CORPORATION OF OHIO.

GAS COOLER.

Application filed October 12, 1922. Serial No. 594,112.

To all whom it may concern:

Be it known that I, HENRY HOWARD, a citizen of the United States, residing at Cleveland, in the county of Cuyahoga and State of Ohio, have invented certain new and useful Improvements in Gas Coolers, of which the following is a specification.

The invention relates to a device for cooling hot gases, particularly the hot sulfur dioxid gases, such as are produced in pyrites or sulfur burners, which must be cooled prior to their use in the manufacture of sulfuric acid.

Heretofore coolers of this type, for example that shown in Patent No. 1,078,841, have consisted of a cylindrical shell immersed in a surrounding tank constituting a deep water jacket. As the shells are usually made of lead, the hydrostatic pressure, due to the depth of the cooling water on the outside of the shell, was so great that the lead shell tended to buckle inwardly thereby causing leaks and necessitating complete rebuilding of the apparatus. These shells moreover had to be made of thick lead castings which made the construction heavy and costly, and it was found difficult to make these heavy castings free from sand holes which in course of time developed serious leaks.

These objections I have overcome in the construction shown in the accompanying drawing in which:

Fig. 1 is a longitudinal vertical section of the cooler, and

Fig. 2 is an enlarged sectional view of a detail thereof.

The cooler proper comprises a shell 1, which is preferably cylindrical in cross-section and which may be made of rolled lead about one-half inch thick, a cover 2, and a tapered bottom 3. The cover 2 may be made of material similar to that of the cylindrical shell 1. The shell 1 rests on the top 4 of a suitable iron frame 5 which is provided with a tapering lead-lined inner wall or pan 6 forming the bottom portion 3 of the gas chamber. Frame 5 is in turn supported by a suitable masonry base 7 formed centrally with a well 8 into which the bottom 3 of the shell depends. A suitable lead-lined collector 9 may be placed in the well 8 beneath and around the open lower end 10 of the shell or cooling chamber. A suitable lead-lined offtake 11 communicates with the in-

terior of the shell, preferably through the tapered bottom 3, as shown.

The gas to be cooled is introduced at the top of the cooler through an opening 12 in the cover 2. The latter sets upon a flaring lined seat 13 supported by the frame 5 through the medium of beams or other standards 14. A number of openings or manholes 15, one only of which is illustrated, are provided in the cover 2 for periodic flushing of the interior of the shell with hose or the like, and to facilitate manipulation of the hose the openings 15 are preferably conical in section as indicated in the drawing.

The characteristics of the cooler which more specifically have to do with my novel improvements will now be described. It will be noted from the drawing that the cover 2 is so shaped and seated that between it and the seat 13 there is formed a basin 16 of substantial depth and capacity. This basin is supplied in any suitable manner with water which, after a predetermined height is reached, overflows through one or more pipes 17. In this manner the cover is maintained sufficiently cool to withstand the excessive temperatures incident to the introduction of the gas into the cooler.

Surrounding the shell 1 are a series of superposed annular troughs 18, open at the tops thereof and converging to fit tightly at their bottoms against the outer side of the shell. A water-tight engagement is insured preferably by a lap-joint construction such as is illustrated in Fig. 2 wherein an annular inclined rim 19, which abuts against the lower and outer surface of the trough, is provided with a depending collar 20 by which the rim is secured, as by burning or like, to the shell 1. The troughs are supported at their upper edges by the standards 14. For this purpose annular bands 21 may be bolted or otherwise secured to the standards 14 and receive flanges 22 at the tops of the troughs 18. Each trough communicates with the one next below by means of one or more lead overflow pipes 23. The pipes piercing any one trough are of course not in vertical alinement with the pipes 105 piercing the adjacent troughs, and preferably and arranged diametrically opposite one another as illustrated.

Pipe 17 conducts the overflow from the cover receptacle 16 to the uppermost trough 110

18 from which it flows to the succeeding troughs, seriatim, through the overflow pipes 23, as will be readily understood. The hot gas to be cooled, for example sulfur dioxid,
5 enters the chamber at the opening 12 and the cooled gas passes off through the outlet 11.

Preferably adjacent troughs or pockets 18 overlap each other a few inches, as indicated, and the top of each overflow pipe is
10 set about midway between the plane of the top of the trough and the plane of the junction of the rim and shell. This arrangement gives a certain leeway to prevent overflowing of the water at the tops of the troughs
15 and at the same time insures such a level of water that it will overlap the bottom of the next higher trough by, say, a couple of inches. Thus the shell 1 is completely jacked-
eted with water.

20 Suitable means, not shown, controlled for example by the flow of the water from the lowermost overflow pipe 23', may be employed to operate an alarm when the flow of cooling-liquid diminishes to a material
25 degree or ceases.

There are numerous advantages attending the use of my improvements. Of these I may mention the following:

(1) The dangers resulting from stoppage
30 of the water-supply are minimized, since it would be necessary, after the water-supply stops, to actually evaporate off a considerable quantity of water before the danger point would be reached, and this probably
35 would require at least an hour's operation;

(2) The arrangement of the troughs affords exceedingly good support to the lead shell;

(3) The cover of the cooler serves as a

water-receptacle, no part being in contact with the hot gas which is not water-cooled.

(4) The lead-lined iron pan forming the bottom of the cooler serves as an acid lute and permits removal of mud etc. without interfering with the operation of the cooler. 45 This is especially important when burning fine pyrites.

Other advantages will occur to those skilled in the art.

I claim:—

1. A cooling apparatus comprising a metal shell, a cover having a gas inlet therein, a closed bottom portion having a gas outlet, a series of superposed annular troughs surrounding the shell and having their lower 55 ends in water-tight engagement therewith, and an overflow conduit extending downwardly through the wall of each trough, the upper end of the conduit being below the upper edge of each trough through which 60 it extends and the lower end arranged to deliver cooling liquid to the trough below.

2. An apparatus as claimed in claim 1 in which the troughs overlap and the upper end of each conduit is above the lower end 65 of the trough above.

3. An apparatus as claimed in claim 1 in which the overflow conduits of each adjacent pair of troughs are on opposite sides of the shell.

4. An apparatus as claimed in claim 1 in which the cover is formed as a water receptacle and provided with an overflow pipe extending from near the upper edge thereof 75 into the uppermost trough.

In testimony whereof, I affix my signature.

HENRY HOWARD.
